UNITED STATES PATENT OFFICE.

FRANK DATHAN, OF OAKLAND, CALIFORNIA.

PNEUMATIC PLAYER-PIANO ACTION.

1,390,430.

Specification of Letters Patent. Patented Sept. 13, 1921.

Application filed October 23, 1917. Serial No. 198,053.

To all whom it may concern:

Be it known that I, FRANK DATHAN, a citizen of the United States, residing at Oakland, in the county of Alameda and State of California, have invented certain new and useful Improvements in Pneumatic Player-Piano Actions, of which the following is a specification.

This invention is an improved pneumatic piano player action.

One of the objects of the invention is to simplify the mechanism of such actions, reduce the size and number of necessary working parts, and to materially reduce the friction of said parts. A further object is to make an auxiliary pneumatic action of such construction that it can be built into an upright straight piano or be installed in one already manufactured. A further object is to provide in a pneumatic action a supplementary pneumatic bellows with means for governing, at the option of an operator, the action and degree of force applied by the primary bellows to any blow or movement coming within the function of said primary bellows. A further object is to provide in a pneumatic piano action means for varying a tone by controlling the force of the blow applied to vibrate the string. A further object is to provide a simplified means of attachment of said pneumatic action to any standard piano action, becoming a part thereof and easily removable therewith.

The invention will be hereinafter fully set forth and particularly pointed out in the claims.

In the accompanying drawings:

Figure 1 is a vertical section of a pneumatic bellows with my auxiliary bellows in position thereon. Fig. 2 is a side view of a piano action with the pneumatics in operative position thereon. Fig. 2^a is a detail sectional view illustrating the removable extant rail. Fig. 2^b is a detail view illustrating the pivotal support of the shelf carrying the master valve chest. Fig. 3 is a longitudinal section of a master valve chest. Fig. 4 is a vertical central section of a valve chest of my auxiliary pneumatic bellows. Fig. 5 is a central section of a keyed showing a lever controlling air intake valves. Fig. 6 is a detail view of the valve stem bearing.

Referring to the drawings, 1 indicates the base of a master valve chest, having in its

nether surface, a longitudinal groove 2. Extending throughout the length of groove 2 is a strip of celluloid 3, retained in position by glue or other means, and having ports or bleed holes 4, at intervals throughout its length, which register with larger ports 6, closed by valves 8, positioned to engage valve seats 7. Each valve 8 is in the form of a pouch valve with a stiff disk on top positioned to engage and raise a valve stem 9, which has its bearing in a convoluted wire 11, bent and sharpened at its ends to enter the lower surface of a central partition 12 of the valve chest. The groove 2 forms an exhaust channel connected with an air-exhausting device of any preferred type (not shown).

The valve stem 9, carries a valve 15, in a chamber 13. When atmospheric air enters the bore 6 through the tube 21, valve 8 is raised, whereupon said valve 15 is raised, a vacuum in the lower chamber of the valve chest sucks through a port 14, leading through a fixed wall 16, of a pneumatic bellows, collapsing the said bellows until movable wall 17 of said bellows encounters a stock 18, illustrated as consisting of a washer on the threaded end of a screw 19, extending through the wall 16 of said bellows. The screw 19 affords a means of adjusting the movement of said bellows to a predetermined degree. The vacuum operating means of the bellows is of usual construction, the master valve chest being connected by lateral branches 6^a from ports 6, and pipes 21 to a tracker bar.

It is desirable to afford a means in pneumatic piano actions of varying a tone to suit the player and I have accomplished this by a structure which is attached to the mechanical player and may be operated manually at will be the player. Suitably attached to the fixed wall of each bellows, is a bracket 22, to which is secured one wall 23, of a minor or auxiliary bellows, smaller than the bellows of the action proper. On the outer surface of a collapsible wall 24 of said auxiliary bellows, is secured one end of a tension spring 26, the other end of which is connected to a cleat 27, attached to the collapsible wall 17 of the major bellows.

The minor bellows is controlled by a port in a nipple 28, leading from the interior of said bellows to a minor valve chest 29, having nipples a, b, and c. The inlets of the ports of nipples, a, b, and c are controlled by

separate valves 31, of like construction, hinged to one wall of the valve chest and pressed toward the respective ports by springs 32, to a degree regulated by screws 33, working in the wall of the chest.

5 Pipes 34 lead from the nipples *a*, *b* and *c* to the upper ends of nipples 36 in the key bed of the piano. The other ends *a'*, *b'* and *c'* of nipples 36 in said keybed are closed by 10 a flexible spring 37, one end of which is rigidly secured to the nether surface of said keybed, by a screw 38, and the other end of which is slidable, because of a slot 39 in the said spring 37, on a screw 41. The said spring 37 is depressible by a lever 42 pivoted in a bearing 43 secured to the nether surface of the spring. It will be seen that by reason of this construction the opening of the ports 36 may be accomplished in steps or degrees, 15 thereby producing different effects on the auxiliary bellows which in turn advances or retards the movement of the primary bellows. It is to be understood that there is one auxiliary pneumatic 24 for each pneumatic 17 and one of the latter for each note 20 of the piano.

I have effected a considerable saving in the number of parts required and in the space necessary to inclose the action by 30 adopting a vertical position for the bellows or pneumatics. Also simplified in like manner is the mode of attachment of pneumatic to striker. For instance, on the back of the collapsible wall 17, of the major bellows, 35 I have secured a cleat 44, having a rounded lip 46, and a notch 47, for engaging a looped end of a flexible wire or tape 48, the other end of which surrounds one end of a wire 49. The wire 49 is threaded at each end. 40 Two washers 51, of rubber or fibrous material, are secured on one threaded end of wire 49, between which is the flexible wire 48. The other threaded end of wire 49, is screwed into the wood of that part of a piano action known as the wippen, here designated as 50. I have found from experience that in addition to the advantages of economy of space and material this construction results in a greatly improved actuating 45 means by reason of the right angled leverage afforded by the wires 48 and 49.

In order to facilitate the repair of adjustment of the working parts of my improved action, I have adopted the novel mode of 55 attachment shown in Fig. 2. The base 1 of the master valve chest is screwed, as shown at 52, to a shelf 53, which is pivoted on a screw 54, to an iron bracket 56, commonly used in piano structures. The entire pneumatic action can be swung downwardly into 60 the dotted position shown in Fig. 2, affording

easy access to the backs of the individual bellows. The shelf 53 is held in horizontal position by a pin 57 extending through a portion of said shelf into a hole in the iron 65 brackets 56.

In order to further improve the accessibility of the action, I have made a removable extension rail 58, with a wedge shaped vertical groove 59 in its face, making it slidable 70 vertically on a screw 61. It is possible to lift out this rail without removing the screw 61.

Having thus explained the nature of the invention, and described an operative manner of constructing and using the same, although without attempting to set forth all of the forms in which it may be made, or all of the forms of its use, the following is claimed:—

1. An improvement in player pianos comprising striker pneumatics and means for operating the same, a wippen, an operating wire attached thereto, and a single integral flexible means secured at one end to said wire and connected at the other end with one wall 85 of said pneumatic.

2. An improvement in player pianos comprising a striker pneumatic and means for operating the same, a wippen, an operating wire attached thereto, a cleat attached to a 90 movable part of the pneumatic, and a single integral flexible means provided at one end with a loop engaging said cleat and having its other end secured to said wire.

3. An improvement in player pianos comprising a master valve chest and pneumatics supported thereby, a shelf on which said valve chest is superposed, pivotal supporting means for said shelf, and means for normally preventing pivotal movement of the shelf. 95

4. An improvement in player pianos comprising a master valve chest and pneumatics supported thereby, a shelf on which said valve chest is superposed, a support bracket, a pivotal connection between said shelf and 100 said bracket, and means for preventing pivotal movement of the shelf.

5. An improvement in player pianos comprising a master valve chest and pneumatics supported thereby, a shelf on which said valve chest is superposed, a bracket supporting said shelf, and an extension rail movably 110 engaging said bracket.

6. An improvement in player pianos comprising a master valve chest and pneumatics supported thereby, a shelf on which said valve chest is superposed, a bracket supporting said shelf, and a rail provided with a wedge groove in one face, said bracket having a projection to engage said groove. 115

In testimony whereof I affix my signature.

FRANK DATHAN.
